CLARENCE A. BIRD, OF WEST MANSFIELD, OHIO.

SWINGLETREE CONNECTION.

1,243,581.

Specification of Letters Patent. Patented Oct. 16, 1917.

Application filed April 13, 1917. Serial No. 161,818.

To all whom it may concern:

Be it known that I, CLARENCE A. BIRD, a citizen of the United States, residing at West Mansfield, in the county of Logan 5 and State of Ohio, have invented new and useful Improvements in Swingletree Connections, of which the following is a specification.

Swingletrees are generally loosely mounted upon the doubletree or other support, and are consequently susceptible of a swinging or swaying motion, especially when the animal is traveling down grade. In addition to constantly swinging against the hind 15 legs of the animal with a detrimental effect, the loose mounting of the swingletrees is very objectionable in that their disposition beneath the doubletree or other support, renders the hitching or unhitching of 20 the animal to or from said trees difficult and inconvenient.

It is therefore the chief characteristic of this invention, to provide a means whereby a swingletree can be maintained in a position above the doubletree or other support, and yet afforded relative movement with respect thereto to compensate for change in the direction of draft, and in which position of the swingletree the objection of 30 the swinging of such elements is eliminated.

The invention has numerous other objects in view, which will appear as the following detail description of the invention is taken into consideration in connection 35 with the accompanying drawing, the invention residing in the construction, combination and arrangement of parts as claimed.

In the drawing forming part of this specification like numerals of reference indicate similar parts in the several views 40 and wherein:

Figure 1 is a perspective view of the invention.

Fig. 2 is a similar view of one of the 45 socket members.

Fig. 3 is a fragmentary view of the yieldable arm.

Fig. 4 is an enlarged detail view of the 50 arm and socket associated.

Fig. 5 is a bottom plan view of the doubletree showing the manner of attaching the socket.

Referring more particularly to the drawing in detail A indicates the doubletree 55 which is swingingly mounted upon the pole B in any suitable manner, while projecting

forwardly from the doubletree at each end is a loop 10 connected with each of which is a swingletree 11.

With a view of maintaining the swingletree above the doubletree, for the purposes hereinabove mentioned, I preferably make use of a yieldable arm 12, which may be constructed from any suitable material, preferably from resilient wire and formed adjacent one end to provide a resilient coil 13. The arm is carried by the doubletree, and may be secured directly thereto, or in any other suitable manner, so that the hook-like extremity 14 thereof will be disposed immediately above the swingletree. Secured to the swingletree 11 at an appropriate point, is a wire element formed with an intermediate bulged portion 15, and eyes 16 at its opposite extremities, to which suitable fastening elements such as screws or the like are passed for securing the element to the swingletree. A link 17 provides a connection between the hook-like extremity 14 of the yieldable arm and the swingletree 11, as the link is connected as shown, with the bulged portion 15 of the wire element. The link is designed to permit of a certain amount of play between the swingletree 11 and the arm 12 when the swingletree is under draft tension, while the yieldability of the arm 12 also provides for movement of the swingletree with respect to the doubletree to compensate for the change in the direction of draft when the swingletree is under draft tension.

Manifestly with the swingletree supported above the doubletree, or other support, in the manner shown in Fig. 1, the swingletree is not permitted to swing loosely against the hind legs of the animal, as is frequently the case with the present day manner of mounting the swingletrees, while in addition to this fact the swingletrees are supported in a position to permit the animal to be hitched closer to the wagon, and the duty of hitching and unhitching of the animal can be more conveniently and easily performed.

As hereinabove stated the yieldable arm 105 may be connected with the doubletree in any suitable manner, but by preference use is made of socket members of the type illustrated in Fig. 2. These members are made in pairs for the right and left hand end of the doubletree, each embodying a substantially L-shaped attaching plate, the branches

18 and 19 of which are disposed at an angle as shown, so that the respective branches can properly engage the underside and rear edge of the doubletree, in the manner to dispose 5 the socket member 20 immediately behind and in alinement with the transverse center of the swingletree. The long branch 18 of each attaching plate is provided with openings 21 through which suitable fastening elements may pass into the doubletree for securing the plate thereto. The socket 10 20 is adapted to receive the short extremity of the arm 12 to support the latter, while this extremity of the arm is offset as at 22. 15 The offset portion is adapted to enter a transverse slot 23 in the socket member adjacent the lower edge thereof, when the arm and socket are operatively associated, with a view of preventing the arm from working 20 upwardly, and becoming casually disengaged from the socket. The proportion of the socket and short extremity of the arm 12 is such, that when these parts are associated the coil 13 will be spaced a slight distance 25 above the doubletree, thus providing a clearance space for any clevis that may be attached to the doubletree. The slot 23 is elongated to permit the arm to turn for a limited distance, should the team seesaw 30 as is frequently the case. The invention is not only simple in construction, and very meritorious for the purpose intended, but it can be readily and easily applied to a doubletree or other support, in connection with 35 a swingletree, without changing the construction of either.

While it is believed that from the foregoing description the nature and advantages of the invention will be readily apparent, I desire to have it understood that what is herein shown and described constitutes the preferred embodiment of the invention, to which I do not limit myself, and that such changes in the construction, combination 45 and arrangement of parts may be resorted to when desired as fall within the scope of what is claimed.

What is claimed is:—

1. A swingletree connection comprising in

combination with a support, a socket member secured to the latter and having a transverse slot adjacent one end, a resilient arm having one extremity fitted within the socket, said extremity of the arm being formed with an offset portion to be received 55 within said slot for holding the arm within the socket, and permitting said arm a limited swinging movement, said arm projecting 60 forwardly across said support and spaced therefrom, and the free extremity of 65 said arm suspending the swingletree in a position above said support.

2. Means for supporting a swingletree above the doubletree, said means including a vertically disposed yieldable arm having one 65 terminal connected to the swingletree and its opposite terminal connected with the doubletree, a resilient coil formed in the length of said arm and positioned above the doubletree, and said arm being mounted 70 upon the doubletree for partial rotation in opposite directions.

3. A swingletree connection comprising in combination with a doubletree, a socket, means for attaching the socket to said support whereby the latter will be disposed vertically adjacent one edge thereof, a resilient arm having one extremity fitted in the socket and its opposite extremity connected with the swingletree for holding the latter 80 spaced above said support, and a resilient coil formed in the arm and disposed above said support.

4. A swingletree connection comprising in combination with a doubletree, a socket disposed in a vertical plane at the rear of the doubletree, angularly disposed attaching plates forming part of the socket and adapted to be secured to the bottom and one longitudinal edge of the doubletree, a resilient 90 arm having one extremity fitted within the socket and having its oposite extremity projecting forwardly in advance of said support, the latter mentioned extremity of said arm suspending the swingletree therefrom 95 in a position above the doubletree.

In testimony whereof I affix my signature.
CLARENCE A. BIRD.
